(57) **CLAIM**

The ornamental design for a spray head, as shown and described.

DESCRIPTION

In a preferred embodiment, the nature of this product is a spray head for spraying a human with a water shower.

FIG. 1 is a right, top, front perspective view of a spray head according to my new design;

FIG. 2 is a front elevational view thereof;

FIG. 3 is a right side elevational view thereof, the left side elevational view thereof being a mirror image of the right side shown;

FIG. 4 is a top plan view thereof, the bottom plan view thereof being a mirror image of the top view shown; and,

FIG. 5 is a rear elevational view thereof.

The broken line representations of holes in FIGS. 1-4 and of mounting structure in the figures are for the purpose of illustration only, and form no part of the claimed design.
